UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

SHEET-PRINTING MACHINE.

1,095,528.

Specification of Letters Patent. Patented May 5, 1914.

Application filed July 9, 1912. Serial No. 708,471.

To all whom it may concern:

Be it known that I, EDWARD P. SHELDON, a citizen of the United States, residing at New York, county of Kings, and State of New York, have invented certain new and useful Improvements in Sheet-Printing Machines, fully described and represented in the following specification and the accompanying drawings, forming a part of the same.

This invention relates to certain improvements in sheet printing machines.

In printing sheets which are to receive more than one impression it is usual to deliver the sheet after each impression, the sheets being piled. The sheets from this pile are then again run through another or the same machine to receive an additional impression. This requires additional handling of the sheets and there is, further, liability of offsetting unless the practice of using slip sheets is resorted to.

The present invention has for its object to produce an improved printing machine for printing on sheets by which the piling and additional handling of the sheets between impressions is avoided, the machine embodying a single printing couple and means for automatically successively presenting sheets to different parts of the couple to receive successive impressions.

With this and other objects not specifically referred to in view, the invention consists in certain constructions and in certain parts, improvements and combinations as will be hereinafter described and then specifically pointed out.

Referring to the drawings:—Figure 1 is a plan view of so much of a printing machine constructed in accordance with the invention as is necessary to an understanding thereof. Fig. 2 is a side elevation of the construction shown in Fig. 1. Fig. 3 is a detail view.

Machines embodying the invention will include what is herein termed a multiple wide printing couple, that is to say, a printing couple the lengthwise printing capacity of which is a multiple of the sheet to be printed. The particular form of couple which has been selected for the purpose of illustrating the invention comprises an impression cylinder 1 and a printing cylinder 2, this cylinder being of the character known as an offset printing cylinder. This cylinder

2 will be provided with the usual offset printing surface, such as a rubber blanket, and receives its design from a cylinder 3, the construction being well-known in the art. The length of the cylinders is a multiple of the width of the sheets to be printed.

Means will be provided for presenting a sheet to one part of the printing couple to receive the first impression. While these means may be varied, in the particular construction illustrated, they comprise a feed-board 4 by which the sheets are delivered to grippers 5 on the cylinder 1. Suitable registering devices to insure the proper presentation of the sheets to the grippers may be employed. While these registering devices may be of any suitable character, in the construction shown they consist of the ordinary front stop 6 mounted on a rock shaft 7 operated by mechanism ordinarily employed for this purpose. After the sheets have been presented to one part of the printing couple and printed thereby, they will, in machines embodying the invention, be again presented to another part of the couple to receive another impression. While the means for effecting this second presentation of the sheet to the printing couple may be varied, in the particular construction shown they include a pair of sheet receiving cylinders 8, 9, these cylinders being provided with grippers 10 and 11 respectively.

In the best constructions embodying the invention the sheet receiving mechanism will cooperate with suitable means for effecting a sidewise transfer of the sheet. While this transferring mechanism may be varied, in the particular construction illustrated, there is provided a frame 12 which has a series of diagonally arranged rollers 13 mounted thereon. When rollers, such as have been referred to, are employed to effect the sidewise transfer of the sheet they may be operated in any suitable manner. In the particular construction illustrated, each roller is provided with a sprocket 14 and these sprockets are engaged by two sprocket chains 15. One of these sprocket chains 15 runs around a driving sprocket 16 mounted on a shaft 17 provided with a bevel gear 18 meshing with a bevel gear 19 mounted on a standing shaft 20 driven in any suitable way from the driving mechanism of the machine. In the machine illustrated, as the sheet is carried around by the cylinder 9, the grip-

pers of the cylinder open and the sheet is delivered onto the rollers 13 on the frame 12, the delivery being assisted by a propeller roll 21 and a stripper or guide 22. The sheet will, therefore, be given a sidewise travel by the rollers and at the same time advanced toward the front guides, this being due to the diagonal arrangement of the rollers. Suitable means, such as a guide, should be provided for determining the amount of sidewise travel of the sheet, so that it may be brought into proper register to be again delivered to the printing couple. In the construction shown, a side guide 23 is provided for this purpose.

In machines embodying the invention in its best form, a suitable stop will be provided so as to prevent the sheet from coming against the front stops 6 before the stops are positioned to receive them. While the stop may be of any suitable character, in the particular construction shown, a rock shaft 24 carrying stop fingers 25 is provided for this purpose. This shaft 24 will be rocked at any desired time by suitable connections from the machine.

Changes and variations may be made in the construction by which the invention is carried into effect. The invention claimed, therefore, is not to be confined to the particular construction herein shown and described.

What is claimed is:—

1. The combination with a multiple wide printing couple, of means constituting an entering sheet path for presenting a sheet to one part of the couple to be printed thereby, means for receiving the sheet from said part and turning it, and means out of the entering sheet path for taking the sheet from said receiving means and simultaneously moving said sheet laterally and forward for presentation to the next part of the printing couple.

2. The combination with a multiple wide printing couple, of means constituting an entering sheet path for presenting a sheet to one part of the couple to be printed thereby, a receiving mechanism for taking the sheet after printing, and means cooperating with the receiving mechanism and out of the entering sheet path for delivering the sheet to another part of the couple to receive another printing.

3. The combination with a multiple wide printing couple, of means constituting an entering sheet path for presenting a sheet to one part of the couple to be printed there-

by, a receiving mechanism for taking the sheet after printing, and means, out of the entering sheet path, including a transferring mechanism and a suitable registering guide for delivering the sheet to another part of the couple to receive another printing.

4. The combination with a rotary multiple wide printing couple, of means constituting an entering sheet path for presenting a sheet to one part of the couple to be printed thereby, a rotary sheet receiving mechanism for taking the sheet after printing, and means out of the entering sheet path and coöperating with the receiving mechanism for again delivering the sheet to the couple to receive another printing.

5. The combination with a rotary multiple wide printing couple, of means constituting an entering sheet path and including suitable front stops for presenting a sheet to one part of the couple to be printed thereby, a rotary sheet receiving mechanism for taking the sheet after printing, and means out of the entering sheet path and including a transfferer and suitable side guide for presenting the sheet to another part of the couple to receive another printing.

6. The combination with a rotary multiple wide printing couple, of means constituting an entering sheet path and including suitable sheet stops for presenting a sheet thereto to receive a printing therefrom, a rotary sheet receiving mechanism for taking the sheet after printing, a transfferer located out of the entering sheet path and embodying diagonally arranged rollers, and means for registering the sheet sidewise, whereby the sheet may be again presented to the printing couple to receive another printing therefrom.

7. The combination with a rotary multiple wide printing couple, of means for presenting a sheet to one end thereof to be printed thereby, a pair of sheet receiving cylinders for taking the sheet, a set of diagonally arranged transferring rolls to take the sheet from the receiving cylinder, shift it sidewise and present it to the couple to receive another printing, and suitable registering devices.

In testimony whereof, I have hereunto set my hand, in the presence of two subscribing witnesses.

EDWARD P. SHELDON.
